UNITED STATES PATENT OFFICE.

EDWARD J. FISCHER, OF CINCINNATI, OHIO.

DESIGN FOR A TALKING-MACHINE CABINET.

49,300.

Specification for Design.

Patented July 4, 1916.

Application filed April 14, 1916. Serial No. 91,257. Term of patent 3½ years.

To all whom it may concern:

Be it known that I, EDWARD J. FISCHER, a citizen of the United States, residing at Cincinnati, in the county of Hamilton and State of Ohio, have invented a new, original, and ornamental Design for a Talking-Machine Cabinet, of which the following is a specification, reference being had to the accompanying drawing, forming part thereof.

Figure 1 is a front view of a talking machine cabinet illustrating my new design, and Fig. 2, is a side view thereof.

I claim:

The ornamental design for a talking machine cabinet, as shown.

Witness my hand at the city of Cincinnati, in the county of Hamilton, and State of Ohio, this 10th day of April, 1916.

EDWARD J. FISCHER.

Witnesses:

ALBERT W. ALDEMAYER,
H. E. CARSTENS.
